PARKING FINE DEPOSIT BOX

Rinaldo Sciacero, Chicago, Ill., assignor to Miller
Meters, Inc.

Application April 19, 1954, Serial No. 30,086

Term of patent 14 years

(Cl. D52—3)

Fig. 1.

Fig. 2.

Fig. 1 is a front perspective view of a parking fine deposit box, showing my new design; and

Fig. 2 is a rear perspective view thereof.

The opposite side of the parking fine deposit box is substantially the same in appearance as the side seen in the drawing.

I claim:

The ornamental design for a parking fine deposit box, as shown and described.
